UNITED STATES PATENT OFFICE.

WILLIAM SCHOLNHORN, OF NEW HAVEN, CONNECTICUT, ASSIGNOR TO
WILLIAM SCHOLNHORN & CO.

SHEARS.

SPECIFICATION forming part of Letters Patent No. 314,729, dated March 31, 1885.

Application filed October 20, 1884. (Model.)

To all whom it may concern:

Be it known that I, WILLIAM SCHOLNHORN, of New Haven, in the county of New Haven and State of Connecticut, have invented new 5 Improvements in Shears; and I do hereby declare the following, when taken in connection with accompanying drawings and the letters of reference marked thereon, to be a full, clear, and exact description of the same, and which 10 said drawings constitute part of this specification, and represent, in—

Figure 1, a side view; Fig. 2, a longitudinal central section through the pivot.

This invention relates to an improvement 15 in pivoting the blades of shears, adapted principally to the larger class of shears. In the more general construction of such shears, the pivot consists of a headed screw passing through the two blades, tapped into one, the 20 head taking a bearing upon the other. In some cases it is made in the form of a bolt, a large head upon one side to bear upon one blade and a like nut upon the opposite side screwed upon the bolt, and to bear against 25 the opposite blade. In either case, unless the blades work with perfect freedom, the screw is liable to loosen, as in the first instance—that is, the headed screw—the pivot must hold fast in the blade into which it is screwed, the 30 other blade turning freely on the pivot and against the head, lest through lack of lubricant, or through friction otherwise produced, the blade which turns free so engages the head as to turn the screw. In the second case the diffi- 35 culty is increased because of one blade working against the head of the pivot, and the other against the nut on the other end of the pivot, but either of the blades are liable to so engage the head or nut, as the case may be, 40 by frictional contact sufficient to turn the one from the other and thereby loosen the pivot.

The object of my invention is the construction of a pivot whereby the blades may be properly adjusted, and, once adjusted, held 45 firm without liability of derangement, and also so as to give a large firm bearing for the blades to turn upon; and the invention consists in the construction of the pivot and its arrangement in the blades, as more fully hereinafter 50 described, and particularly recited in the claim.

A represents the one blade; B, the other, of common construction. C, the body of the pivot, is screw-threaded, and the one blade A correspondingly screw-threaded. The head of the 55 pivot is constructed with a shoulder, *a*, upon its under side, of a diameter between that of the body C of the pivot and the head D. The blade B is bored corresponding to the body of the pivot, and counterbored for the shoulder 60 *a*, as seen in Fig. 2. The pivot is of sufficient length to extend through the blade A, and so as to receive a nut, E, upon the side opposite the head. This nut serves as a jam-nut to hold the pivot in the blade A at any position 65 to which it may be set. The blades are set together and the pivot introduced, the shoulder *a* of the head coming to a bearing in the counterbore and the head itself upon a bearing upon the outside of the blade B. It is 70 screwed into the blade A until the two blades are brought into their proper relation to each other, then the nut E is applied to the screw end of the pivot and turned to a firm bearing upon the blade A, as a jam-nut, to lock the 75 pivot in that position. The pivot once properly arranged retains that position without possibility of readjustment in the working of the blades. The shoulder *a* forms a large bearing upon which the blade B will oscillate, 80 and the head D, as well as the under side of the shoulder *a*, forms a large bearing, against which the side of the blade will work. This construction adds but a trifling cost in the manufacture of the class of shears to which it 85 is adapted, and overcomes serious difficulties in the pivots of such shears as heretofore generally made.

I am aware that a headed rivet having a screw-thread upon its shank has been introduced through one of the blades to bring the head of the rivet upon that blade, and screwed into the other blade, the screwed end portion of the rivet extending through said second blade, with a jam-nut applied thereto, 95 and therefore do not broadly claim such a construction.

I claim—

The herein-described improvement in shears, consisting of the pivot composed of a screw-threaded body, C, head D on one end, shoulder *a* directly under the head and of a dia- 100

ter between that of the body and of the head, the body of the pivot of a length greater than the thickness of the two blades, the one blade constructed with an opening for the pivot 5 and with a counterbore corresponding to the shoulder *a* beneath the head of the pivot, the other blade having a corresponding opening screw-threaded to correspond to the screw-thread on the body of the pivot, the pivot introduced through the one blade to bring the 10 said shoulder *a* to a bearing in the counterbore and the head to a bearing upon the outer

surface of the blade, the opening through the blade also taking a bearing on the body of the pivot, the pivot screwed into the other blade 15 and extending through that blade, combined with a nut, E, on said projecting end of the pivot and against the surface of the blade opposite the head, substantially as described.

WILLIAM SCHOLLHORN.
